POWDER DISPENSER

William H. Rose, Jersey City, N. J., assignor to
 Stanco, Incorporated, a corporation of Delaware

Application July 18, 1936, Serial No. 91,251

5 Claims. (Cl. 221—61)

This invention relates to bellows type dispensing containers for powdered materials. One object of the invention is to provide a means for resiliently expanding the flexible walls of a container so that by intermittent compression of the container walls the contents may be discharged in a fine spray with some degree of force.

The invention may be fully understood from the following specification when read in connection with the accompanying drawing in which

Fig. 1 is a perspective view of a container partly cut away to show the interior and an expansion member in operating position;

15 Fig. 2 is a perspective view of an expansion member flattened to show its conformation;

Fig. 3 is a side view in perspective of the expansion member in a compressed position;

20 Fig. 4 is a perspective view of an alternate form of the invention; and

Fig. 5 is a perspective view of a separator for the expansion member.

Referring to the drawing and in particular to Fig. 1, numeral 1 denotes an envelope container for powder, numeral 2 the powder contents and numeral 3 an expansion member. The envelope 1 may have a flap 4 at one end through which the expansion member may be inserted and the envelope be filled. After the container 25 has been filled this flap may be secured in a conventional manner, as by glue or the like, in order to seal the envelope against escape of powder or air during use except in the manner provided for. A partially perforated portion 30 may be provided at one corner of the envelope and flap as at 5 in order to permit easy removal of that portion to provide a discharge opening for the container.

The expansion member 3 illustrated in Figs. 2 and 3 consists of a generally rectangular flat sheet of a material such as fiber or paper board, slightly narrower than the container in which it is to be used, which may be formed of laminations disposed longitudinally of the sheet. For 45 the purpose of illustration, in these figures a laminated sheet is shown which is deformed, by scoring or impression, eccentrically and laterally of the sheet to create a substantially U-shaped groove 6 therein forming a hinge joint 7 having divergent arms 8 and 9 of which one arm is substantially equal in length to the length of the container. However, the sheet may be scored at a midpoint thereon to form arms of equal length and some of the advantages will be retained. 50 When the arms 8 and 9 are compressed as shown

in Fig. 3, due to the deformation of the sheet, a force is exerted on the laminations, individually and collectively, which tends to stretch them longitudinally of the hinge joint and to compress them laterally thereof. Further, flexure of the member 3 tends to cause a separation of the laminations laterally along the edges of the groove 6 at points 10 and 11. As the material used for member 3 may be only slightly extended the force exerted at the hinge joint 7 and tending to stretch the material is strongly resisted. Likewise, as in manufacture the material has been compressed to only slightly less than the maximum extent, strong resistance to compression is also developed. The resistances developed in such manner are translated into a spring action of the expansion member 3 which is further augmented by the resistance of the laminae to separation. When a one piece or unlaminated sheet is used similar stresses are 20 set up within the material itself and comparable results may be obtained.

Ordinarily the width of the groove 6 is just sufficient to cause the edges thereof, 10 and 11, to bear against one another to form a fulcrum 25 for the arms, but if desired the groove may be widened so that when the arms 8 and 9 are compressed, the edges 10 and 11 bear against the bottom of the groove. The reaction in either case is similar.

The expansion of member 3 within the envelope 1 deforms the envelope sufficiently to create a hollow space therein which forms a powder and air pressure chamber suitable for the purpose desired.

In order to increase the resistance of the expansion member to compression and facilitate more rapid action thereof, a substantially non-resilient separator 12 (Fig. 5), having a thickness slightly greater than that of the slot 13 40 formed by the groove 6 when the arms 8 and 9 are pressed toward each other, may be inserted in the groove. The separator 12 functions to increase the leverage of the arms 8 and 9 thereby 45 increasing the effect of the reaction when the arms are released and causing faster return of the device to its normal position. A suitable element is illustrated in Fig. 5. The separator is maintained in an operative position within the groove by the edges 10 and 11 thereof, as illustrated.

An alternate form of construction is illustrated in Fig. 4 according to which the expansion member 3 consists of a flat sheet of fibrous material having grooves 6 impressed in its surface adjacent

each end, spaced therefrom and from each other to form arms 8 and 9. The arms 8 and 9 are connected by the hinge joints 7, formed by means of the grooves 6, to that portion of the sheet lying between the grooves and indicated by the numeral 14. In this form of the invention the portion 14 is preferably of substantially the same length as the container.

In certain instances an expansion member such as shown in either Figs. 1 or 4 may be reversely folded along the groove 6, with the portion 7 disposed inwardly of the device. It has been found that when folded in this manner the spring action of the member is initially somewhat more rapid.

In use, a container of the type described is filled with powder and the expansion member inserted preferably with the hinge joint 7 adjacent the filling and discharge opening and the end 20 of the longer arm against the other end of the container as is illustrated in Fig. 1.

To operate the device, a corner of the container may be removed and, by exerting intermittent manual pressure upon the sides of the envelope to flex the arms 8 and 9 of the expansion member, a current of air may be forced through the opening made at 5 which will discharge the powder in the container in a fine stream or spray. As pressure on the envelope is intermittently released, a stream of air is drawn into the container by the suction created when the expansion member springs back to its normal position. This incoming current of air will effectively agitate the powder and prevent the discharge of powder in lump form.

The foregoing description is for the purpose of illustration only and the invention is not to be limited by any theories or examples contained therein but only by the accompanying claims in 40 which it is desired to claim all novelty inherent in the invention.

I claim:

1. In a bellows package including a collapsible container an expansion member within the container comprising a flat sheet of fibrous material folded along a U-shaped groove impressed in the sheet laterally thereof so as to form a pair of arms offering resistance to compression sufficient to expand the container when the compressive force is released and in which the edges of said groove engage one another and increase resistance to compression of the arms. 10

2. In a bellows package including a collapsible container an expansion member comprising a flat sheet of fibrous material folded along a pair of U-shaped grooves impressed in the sheet in spaced relation to each other and to the ends 15 of said sheet so as to form a pair of arms offering resistance to compression and in which the edges of said grooves engage one another and increase resistance to compression of the arms.

3. An expansion member according to claim 2 20 in which the flat sheet of fibrous material is grooved laterally at points spaced from each other and from the ends and folded at said points with the grooves faced outwardly.

4. In a bellows package including a collapsible 25 container, an expansion member within the container comprising a flat sheet of fibrous material having a resilient hinge portion formed in the sheet by means of a groove impressed therein at at least one point laterally of the sheet and in 30 spaced relation to the ends so as to form a pair of arms offering resistance to compression sufficient to expand the container when the compressive force is released.

5. An expansion member according to claim 4 35 in which a flat strip of substantially non-resilient material having a thickness slightly greater than that of the slot formed within the hinged portion when the arms are compressed is inserted in a hinge groove to increase the resistance of said arms to compression. 40
